UNITED STATES PATENT OFFICE

157,913

DOCUMENT PHOTOGRAPHING MACHINE

Wallace R. Senechal, North Tonawanda, N. Y., assignor to Remington Rand Inc., New York, N. Y., a corporation of Delaware

Application January 3, 1949, Serial No. 18

Term of patent 14 years

(Cl. D64—11)

To all whom it may concern:

Be it known that Wallace R. Senechal, a citizen of the United States, residing at North Tonawanda, in the county of Niagara and State of New York, has invented a new, original, and ornamental Design for a Document Photographing Machine, of which the following is a specification, reference being had to the accompanying drawings, forming part thereof.

Fig. 1 is a front perspective view of a document photographing machine, showing the new design; and

Fig. 2 is a rear perspective view of the same.

The invention claimed is:

The ornamental design for a document photographing machine, substantially as shown.

WALLACE R. SENECHAL.
